UNITED STATES PATENT OFFICE.

NATHANIEL LOMBARD, OF WORCESTER, MASSACHUSETTS, ASSIGNOR TO LOMBARD CARBURETER COMPANY, OF WORCESTER, MASSACHUSETTS, A CORPORATION OF MASSACHUSETTS.

CARBURETOR.

Original application filed July 11, 1924, Serial No. 725,500. Divided and this application filed November 16, 1925. Serial No. 69,422.

The invention relates to carburetors of the type which lift liquid fuel by suction from a source of supply below the level of the fuel nozzle, and this application is a 5 division of my prior application Serial No. 725,500, series of 1915, filed July 11, 1924, and a continuation, in part, of my copending application Serial No. 656,774, filed August 11, 1923.

10 The main object of the invention is to provide a carburetor of the above type that will lift fuel through a considerable elevation, without creating a detrimentally high vacuum on the intake of the associated 15 engine, and insuring a proper mixture at all variations of speed, throttle position, and variations in height of the fuel supply. To attain this object the invention provides a Venturi passage into which the fuel ports 20 open, thus procuring a powerful suction on the fuel supply without any very great vacuum in the mixing chamber. The invention further provides a diaphragm actuated valve in the fuel line leading to the afore- 25 said fuel ports, and this diaphragm controlled valve is adapted, as in the case of similar prior art devices, to exert a controlling action on the flow of fuel.

I have found, however, that with the elements given above and nothing more, the movement of the diaphragm controlled valve would be magnified by reason of the fact that the suction effect of the engine is, so to speak, stepped up in the desire to attain great lifting effect without a high vacuum at the intake, with the result of giving too rich a mixture to the engine at high speeds, if this valve were not re-controlled by the further mechanism which I 40 have provided. This further mechanism consists in a member in the Venturi passage and suction operated means to move said member relative to the walls of the venturi, thus varying the cross sectional area of the 45 restricted portion of the venturi in accordance with the demand of the engine for the explosive mixture,—this recontrols the action of the diaphragm actuated valve so that the net result is a carburetor of great lifting power giving a proper mixture under 50 all conditions, and without any excessive back pressure.

Self feeding carburetors are not new, and

I do not claim to be the first to use a variable venturi in a carburetor. A successful self feeding carburetor must have a valve controlling the flow of fuel. I believe I am the first to see that, in magnifying the lifting force to attain great lift without excessive back pressure, the ordinary control means for the fuel valve is not enough, but it must be recontrolled as I have outlined, and that this re-control should be self acting and should respond to the variation of the suction of the engine. Desirably the suction means to move the member in the venturi should be created at substantially the same point that the suction to lift the fuel is taken, in order that a proper synchronization may be attained. In the illustrative embodiment of the invention disclosed by the accompanying drawings, and the description relative thereto, this feature is present.

Another object of the invention resides in the specific construction and operation of the movable member in the venturi, and means to check its movement so that in turn the recontrol may not be excessive. This, as well as the main object of the invention, is claimed herein.

In the drawings:

Fig. 1 is a vertical sectional view of a carburetor embodying my invention.

Fig. 2 is a horizontal sectional view along the line 2—2 of Fig. 1, looking in the direction of the arrows.

Fig. 3 is a horizontal sectional view along the line 3—3 of Fig. 1, looking in the direction of the arrows.

Like reference characters refer to like parts in the different figures.

Referring to Fig. 1, the casing or shell of the carburetor is generally indicated at 1 and provides the usual flange 2 to facilitate its attachment to the intake manifold of the engine, not shown. Air enters the carburetor at 3 and passes through a Venturi passage 4, into a mixing chamber 5 on its way to the engine. I show the usual throttle valve at 6. A hollow cylindrical casing 7 is secured to the shell 1 below the air chamber 3, within which fits a hollow piston 8. The piston 8 is provided with a reduced portion 9 slidably within a sleeve 10 extending upwardly from the casing 7. The reduced

portion 9 of the piston terminates in a tapering or ogee valve portion 11, around which a collar 12 tightly fits, and these tapering valve parts tend to seat in the throat of the 5 Venturi passage. The parts 11 and 12, by their form, materially heighten the venturi effect when they are slightly withdrawn from the throat. A coiled spring 13 is received within the portion 9 of the piston 8, 10 and is seated at its lower end on a plate 14 closing the lower end of the casing 7, whereby the pressure of the spring 13 tends to maintain the piston 8 and the tapering portion 11 and collar 12 in the position shown 15 in Fig. 1.

The valve portion 11 is provided with a central opening 15, within which is slidably received a valve stem 16 extending downwardly from a boss 17 located at the top of 20 the shell 1. The lower end of the stem 16 provides a needle valve portion 18, which extends into the constricted opening 19 of a tube 20 carried by the valve portion 11. Above the tube 20 is a space 21 in the tapering 25 portion 11, and this space is connected to the Venturi passage by means of a number of radial and axial passages 22 formed by drilling the tapering portion 11 and grooving its sides before the collar 12 is fitted on, see 30 also Fig. 2.

The tube 20 extends downwardly into a sleeve 23 projecting upwardly from the plate 14, and the lower end of tube 20 carries a piston 24, which is slideable within a hollow 35 cylindrical casing 25 which extends below the plate 14 and is preferably integral therewith. It will be apparent that the parts 8, 9, 11, 12, 20 and 24, being attached together move as a unit, in the functioning of the 40 carburetor.

The end of the casing 25 is closed by a plate 26 which is provided with a central opening 27, normally closed by a check valve 28. The plate 26 is also provided with passages 29 extending radially from the opening 27, which passages 29 communicate with passages 30 extending upwardly through the walls of the casing 25, whereby the small space 31 above the top of the piston 24 is in 45 communication with the opening 27. The space 31 is also in communication with the interior of the tube 20 through a restricted passage 32 provided in the wall of the tube 20, for a purpose to be hereinafter described.

55 The tapering valve portion 11 is also grooved to provide a number of axial passages 33 between it and the collar 12, as in the case of axial passages 22, but the two sets of passages are not intercommunicating. 60 The passages 33 connect the Venturi passage 4 with the interior of the hollow piston 8 and the chamber inclosed within the casing 7. Figure 2 shows the relative arrangement of passages 22 and 33. The space 34 above 65 the piston 8 is brought into communication

with the outside atmospheric pressure, in any suitable manner, such as by an external groove along the portion 9, or a hole through the horizontal portion of the sleeve 10 at 34^a.

When a suction is created by the engine, 70 the interior of the piston 8 will be subjected to this suction, it being communicated by the passages 33, whereupon the piston 8 will move downwardly against the force of the spring 13. Such downward movement will 75 allow a draft of air, entering at 3, to go through the venturi 4 to the engine, and at the same time, the needle valve proper 18 and the tube 20 having been separated, fuel is sucked through the passages 22 and mixes 80 with the air.

It will be noted that the passages 22 open 85 into the venturi 4 practically at the point of maximum air velocity, and the suction thus created will lift fuel from a tank several feet below this point. In the use of my improved carburetor with automobile engines, it is not sufficient, however, merely to lift the fuel, but the flow thereof must be controlled and regulated, and by my invention I have provided means for regulating the flow that is 90 essentially dynamic in its action, so that the results hereinbefore mentioned may be achieved.

95 Proceeding with the description of parts, the plate 26 provides a nipple 35 having an opening 36 in communication with the opening 27, and the nipple 35 is surrounded by a coupling 37 having a passage 38 extending therethrough, in communication with the nipple opening 36. The coupling 37 provides a cup-shaped portion 39, into which the passage 38 opens, and the portion 39 serves as a base for a shell 40, thereby providing an inclosed chamber 41 in direct communication with the opening 27 in the bottom plate 26 of the carburetor. An expansible diaphragm bellows device 42 is located within the shell 40. The upper end of the bellows 42 is carried by a nipple 43 in threaded engagement with a nut 44 secured to the top of the shell 40, a lock nut 45 cooperating with the nipple 43. The nipple 43 has a passage 46, and I desirably provide a cap 47 with an air vent 48 to keep dirt out of the bellows diaphragm 42, while admitting air.

100 The free end of the bellows 42 is provided with a concave seat 49 which, in the position of parts as shown, is just out of contact with a ball 50 provided at the upper end of a valve stem 51. The valve stem 51 extends downwardly into an opening 52 provided in the coupling 37, the stem 51 being provided at its lower end with a valve 53. The valve stem 51 is carried by a spring 54 just below the ball 50 which, when the engine is not running, serves to maintain the valve 53 in engagement with a seat 55, thereby closing the opening 52. That portion of the opening 52 below the valve seat 55 is connected by 105 110 115 120 125 130

a pipe 56 to a supply tank 57, only a portion of which is shown.

In the operation of the improved carburetor, the combined air and fuel valve mechanism described opens more or less in response to the extent of suction created by the engine, the operation of the valve mechanism being very sensitive on account of the venturi effect and the action of the piston 8. 5 However, the said air and fuel valve mechanism will not respond separately to each stroke of the engine on account of the damping action of the piston 24, although when an engine with six or more cylinders is 10 equipped with the carburetor of the present invention, this damping piston may be dispensed with. The restricted passage 32 is provided to prevent an accumulation of air bubbles in the space 31 above the piston 24 15 when the latter is functioning.

The carburetor operates as follows: When the engine to which it is attached is first turned over, the member in the venturi, consisting of the tapering portion 11 and the 25 collar 12, are held upwardly by the spring 13, and so close the venturi. But fuel can be and is drawn into the engine by way of the passages 22, and enough air to create a starting mixture can enter by way of 30 the passages 33. Just when the movable parts 8, 9, 11, 12, 20, and 24 move downwardly varies in different engines according to the power of the starting motor, and is difficult to determine anyway, but it is 35 safe to say that they have opened a little, anyway, as soon as the engine starts to run on its own power. When the engine runs slowly, the vacuum in the chamber 7 will not be great, and so the movable 40 parts above will not have opened the venturi greatly. The magnifying factor of the venturi will therefore be great, and the valve 53 will be substantially opened. When the engine speeds up, the vacuum in the chamber 45 7 will be increased, and the venturi will be opened wider,—thus the magnifying factor will be decreased and the suction exerted to draw the bellows 42 downward and so open the valve 53 wider, while it will inevitably 50 be greater, as it should be, will nevertheless not be so great as it would be if the venturi were a constant area venturi. This re-control of the fuel flow results in a good mixture at all speeds, since without this re-control, 55 the mixture would be excessive at high speeds, or else lean at low speeds.

The exact quantitative nature of this re-control is difficult to determine, but the carburetor shown in the accompanying drawings 60 has been found to give excellent practical results. Therefore I confine myself to indicating the nature of the control over the fuel supply, and am not limited to any merely quantitative results.

65 The functioning of the device is rendered

very smooth by reason of the dash pot device embodied in the cylinder 25 and piston 24. This prevents violent movements of the parts 8, 9, 11, 12, 20, and 24 and thus the re-control is in effect "dampened", and an 70 engine to which the carburetor is attached will run smoothly despite the pulsating nature of the suction created by the engine.

I claim,

1. In a carburetor of the type that lifts 75 liquid fuel from a source below the level of the fuel nozzle, a Venturi passage, a fuel entrance port opening into said Venturi passage at approximately the point of greatest speed of flow of air, thus creating a suction on the fuel which is greater than the vacuum created by the associated engine on the carburetor side of the throttle valve, a fuel line, including suitable connections, connecting said port to the fuel supply, a valve 80 in said fuel line, a pressure responsive device to operate said valve, the said pressure responsive device being actuated and controlled by the suction created in the aforesaid fuel entrance port opening into the said venturi, 85 whereby the valve controlled by the device moves to admit more or less fuel responsive to the changing engine suction and the magnification thereof caused by the entrance port opening into the said venturi, 90 a member in said venturi, and air pressure means for moving said member in relation to the walls of said venturi, said air pressure means being operated by the suction created by the associated engine, whereby to vary 95 the cross sectional area of said venturi where said fuel port opens thereinto, thus preventing excessive action and reaction of the pressure responsive device controlled valve 100 responsive to changes in the demand for fuel 105 by reason of variation of speed of the associated engine and changes in the position of the main throttle valve.

2. In a carburetor of the type that lifts 110 liquid fuel from a source below the level of the fuel nozzle, a Venturi passage, a fuel entrance opening into said Venturi passage at approximately the point of greatest speed of flow of air, thus creating a suction on the fuel which is greater than the vacuum 115 created by the associated engine on the carburetor side of the throttle valve, a fuel line, including suitable connections, connecting said port to the fuel supply, a valve in said fuel line, a pressure responsive device to operate said valve, the said pressure responsive device being actuated and controlled by the suction created in the aforesaid fuel entrance port opening into the said venturi, 120 whereby the valve controlled by the device moves to admit more or less fuel responsive to the changing engine suction and the magnification thereof caused by the entrance port opening into the said venturi, a member 125 in said venturi, an air passage opening 130

- into said venturi adjacent the said fuel port, air pressure operated means operated by the reduction of pressure at the said air passage, said air pressure means being connected to said member to move it in relation to the walls of said venturi, whereby to vary the cross sectional area of said venturi where said fuel port opens thereinto, the said area being thus regulated in accordance with the reduction of pressure at that point, thus preventing excessive action and reaction of the pressure responsive device controlled valve responsive to changes in the demand for fuel by reason of variation of speed of the associated engine and changes in the position of the main throttle valve.
3. In a carburetor, a valve to control the supply of air and liquid fuel, a pair of pistons directly connected to said valve and movable therewith as a unit, cylinders in which said pistons operate, separate passages through said valve leading to said cylinders, one passage admitting the depression in the carburetor to one cylinder to draw said unit against the flow of air, the other passage in said valve carrying liquid fuel from the other
- 5 into said venturi adjacent the said fuel port, air pressure operated means operated by the reduction of pressure at the said air passage, said air pressure means being connected to said member to move it in relation to the walls of said venturi, whereby to vary the cross sectional area of said venturi where said fuel port opens thereinto, the said area being thus regulated in accordance with the reduction of pressure at that point, thus preventing excessive action and reaction of the pressure responsive device controlled valve responsive to changes in the demand for fuel by reason of variation of speed of the associated engine and changes in the position of the main throttle valve.
4. In a carburetor, a conical or ogee valve to control the supply of air and liquid fuel, an orifice adapted to receive said valve, a spring to force said valve against said orifice when the carburetor is inactive, a pair of pistons directly connected to said valve and movable therewith as a unit, cylinders in which said pistons operate, separate passages through said valve leading to said cylinders, one passage admitting the depression in the carburetor to one cylinder to draw said unit against the flow of the air, the other passage in said valve carrying liquid fuel from the other cylinder, where the fuel produces a dash pot effect on the other piston, and a needle valve projecting into said second passage so as to control simultaneously both the air and fuel by movement of the single valve member.
5. In a carburetor, a valve to control the supply of air and liquid fuel, a pair of pistons directly connected to said valve and movable therewith as a unit, cylinders in which said pistons operate, separate passages through said valve leading to said cylinders, one passage admitting the depression in the carburetor to one cylinder to draw said unit against the flow of air, the other passage in said valve carrying liquid fuel from the other cylinder, where the fuel produces a dash pot effect on the other piston, and a needle valve projecting into said second passage so as to control simultaneously both the air and fuel by movement of the single valve member.

Dated this twelfth day of November, 1925.
NATHANIEL LOMBARD.
